UNITED STATES PATENT OFFICE.

EDWARD SUEUR, OF CHICAGO, ILLINOIS.

SPEED-REGULATOR FOR MUSIC-BOXES.

SPECIFICATION forming part of Letters Patent No. 360,396, dated March 29, 1887.

Application filed December 28, 1886. Serial No. 222,763. (No model.)

To all whom it may concern:

Be it known that I, EDWARD SUEUR, a citizen of Switzerland, residing at Chicago, in the county of Cook and State of Illinois, have invented certain new and useful Improvements in Speed Regulators or Governors for Music-Boxes, of which the following is a specification.

Prior to my invention it has been customary to provide fly-regulators for controlling the rate of speed in music-boxes. The fans or wings of the fly in such case are usually made adjustable, so as to vary their angle of impact upon the air, thus increasing or diminishing the resistance to a given surface of wing and modifying the speed. It has, however, been proposed to automatically increase or decrease the area of surface presented by the fans or wings by providing the fly with pivoted weighted arms having flat surfaces, which, upon a high rate of speed, may be swung out in a manner to constitute in effect end extensions of the fans or wings. The manual adjustment of the wings at different angles requires the exercise of skill, which, after the instrument has passed into the hands of a purchaser, is not always available. On the other hand, a variation on the surface presented by the fans or wings, accomplished either automatically or otherwise, while serving to some extent to modify the speed, has a limited utility, since an excessive speed cannot be checked by the mere change of surface presented by the fans. It has also been proposed to employ in connection with organs of that class known as "mechanical" or "self-playing" instruments a chronometric governor, to set the motor to any named time for music or to change from one indicated time to another while the music is being performed, the device in such instance to consist of a pair of governor-arms pivoted to a spindle, and so arranged that when thrown apart they may raise a slide disposed to move up and down in the supporting-frame of the governor, and limited in its up movement at any desired point by a cam-lever, the cam constituting a stop or abutment that will determine the extent to which the slide can rise, according to the position of the cam. Such device, however, is not desirable in connection with the more delicately organized and less powerfully operating mechanism of a music-

box, since the application of the brake is too sudden and positive in its nature, and hence its use might tend rather to create irregularities of speed than to promote steadiness and uniformity of motion.

The object of my invention is to provide an automatically-adjustable speed regulator or governor for a music-box whereby the objectionable features in music-boxes hereinbefore referred to shall be avoided, and to further provide certain novel and improved details of construction in a speed regulator or governor for a music-box, as will hereinafter appear.

To the attainment of the foregoing and other useful ends my invention consists in matters hereinafter described, and particularly pointed out in the claims.

In carrying out the principles of my invention I provide a speed regulator or governor which is connected with and driven from the cylinder—or, what is the same thing, the cylinder-shaft—in a music-box, through the medium of suitable gearing. This speed regulator or governor is provided with a pair of pivoted weighted arms, which are arranged to revolve around the axis of the speed regulator or governor similar to the arms of an ordinary governor for an engine. In connection with these weighted arms I provide a friction device which will operate in the nature of an automatic brake when, by reason of a too-rapid rotation on the part of the cylinder, the governor-arms are thrown outwardly by centrifugal force, in which way the speed will be reduced to its proper standard; and in order to prevent too sudden or positive application of the friction device against a stop or stationary abutment, and to render the action of the friction device sufficiently delicate, I provide between the governor-arms and the friction device a spring or elastic cushion, through which the governor-arms can intermediately act on the friction device, whereby the brake or friction device will be caused to act against the stationary abutment with a yielding pressure, which, however, increases proportionally to the rate of speed, so that should the speed attain an excessively-high rate the brake action will then become positive in its nature. Further improved details will be hereinafter set forth.

In the drawings, Figure 1 represents a top

plan view of a portion of a music-box, the speed-regulator being partially illustrated by a sectional plan taken on the line $x x$ of Fig.

2. Fig. 2 represents in part a transverse vertical section mainly taken on the line $y y$, Fig. 1, the speed regulator or governor being, however, shown partly in elevation and partly in section. In said figure the dotted lines represent the condition of the speed regulator or governor when the weighted arms are by reason of an increase in speed thrown outwardly from their position shown in full lines. Fig. 3 represents in elevation a form of brake or friction device constructed upon the principle 15 of the one shown in Fig. 2, but differing slightly in detail.

The speed regulator or governor is constructed with a pair of weighted rods or arms, A and A', which are pivotally connected at 20 their inner or lower ends with a vertical spindle, B, and normally held proximately parallel with or but slightly diverging from the vertical axis, about which they may be caused to revolve by rotation on the part of the spindle. In order to pivotally connect the weighted arms with the rotary spindle the latter is provided with a cross-piece, b, to the opposite side of which the weighted arms are, respectively, attached by pivots D and D'. Each 25 weighted arm is at its inner pivoted end provided with a laterally-extending finger, so that each of said arms is, in effect, a bent weighted lever pivoted at its bend. The finger or lower lateral extension, a, of the pivoted arm or lever A is arranged at one side of the cross-piece b, while the corresponding finger or lower lateral extension, a', of the pivoted arm or lever A' is arranged at the opposite side of said cross-piece. Both of these said parts or 30 fingers, a and a', are employed for applying power to the brake or friction device, and to such end they are arranged to bear upwardly against the under side of a collar, E, that is fitted loosely upon the spindle B, the said collar being, if desired, provided with a washer, e, against which the fingers a and a' can directly impinge.

The disposition of the weighted pivoted arms to swing outwardly during rotation of the 35 spindle tends to lift the sliding collar E against a spring, C, which is arranged intermediate of the lower collar, E, and an upper collar, E'. This collar E' constitutes the main or acting portion of the brake or friction device, and is likewise loosely arranged upon the spindle, so as to slide up and down thereon. Desirably the lower collar, E, has an upwardly-projecting sleeve or tubular neck, e', through which the spindle passes, while the upper collar, E', is provided with a similar but downwardly-projecting sleeve or tubular neck, e'', through which the spindle also passes. The coiled spring C encircles these two sleeves or tubular extensions and abuts at its ends against 45 the disks or collars E and E'. The said sleeves or tubular extensions e' and e'' are connected together by a sliding joint, which, while caus-

ing them to rotate together, permits them to have independent end movements. Desirably, however, said joint permits a limited rotary play of one sleeve independently of the other, for a purpose hereinafter described.

The sliding joint between the two sleeves can be made in different ways—as, for example, as indicated in Fig. 2, wherein the end 70 portions of the sleeves are partially cut away to substantially form half-tubes, which can interlock with one another, or, as in Fig. 3, wherein one sleeve enters the other, with a stud upon the former arranged to enter a slot 80 in the latter. By such means the two collars with their interlocking sleeves form an extensible hub or sleeve provided with end disks or collars and carrying a spring, which is held between the end collars, the whole constituting a spring-brake or spring-brake cushion. The upper collar, E', which is practically the upper end of the extensible sleeve, is desirably provided with a washer, e', and arranged in juxtaposition to the bearing F, in which the 90 upper end of the spindle B turns.

Should, during operation, the mechanism of the music-box run at too high rate of speed, the weighted arms will by centrifugal action swing out from the center of revolution, thereby 95 serving to lift the lower collar, E, which latter will in turn press upwardly against the spring and cause the same to force the upper collar, E', or the washer on said collar, against the bearing F with a force proportional to the 100 outward movement of the weighted arms. The frictional contact between the brake or friction device and the bearing F will necessarily cause a moderation in the rate of speed, the pressure being decreased or relieved as soon 105 as the mechanism runs at the proper rate of speed. The brake or friction device presses against the bearing F with a yielding pressure, which varies with the rate of speed at which the speed regulator or governor is 110 involved from the mechanism of the music-box, it being observed that the said brake can be arranged to bear either very lightly or exert no appreciable pressure against the bearing F when the apparatus is running at a uniform 115 and proper rate of speed.

Preferably I provide the spindle of the speed regulator or governor with a small cog or gear wheel, G, which is engaged by and driven from a crown or other suitable gear-wheel, H, thereby 120 providing a more durable construction than is commonly attained by the employment of a worm-gear.

The remaining portion of the music-box apparatus or mechanism to which my invention 125 is applied may be of any ordinary or suitable construction and arrangement. As herein shown the spindle of the speed regulator or governor is stepped on a bearing-piece, I, secured to a block, K, from which a standard affording bearing F rises. The connecting mechanism between the cylinder L and the spindle of the speed regulator or governor comprises, for example, a large gear, M, on the axle of 130

the cylinder engaging a small lantern gear or hub, M' , on a gear, M^2 , which latter engages a small lantern gear or hub, M^3 , on the crown-wheel H , the latter being in mesh with the gear G on the spindle of the speed regulator or governor.

The member herein indicated as N is an ordinary pivoted latch employed for automatically stopping the cylinder at the end of each tune played, it being understood that said latch engages a circular groove in wheel M , said groove having a notch in which the latch engages to stop the wheel at the proper moment, as will be readily understood by those familiar with music-boxes without special illustration. This latch can also be utilized for arresting the governor or speed-regulator as soon as the latch has locked the wheel M . Thus, when the latch is in position to lock the wheel M , one of its ends will be brought opposite the cross-piece b of the speed-regulator, as in Fig. 1, while on the other hand, when the latch is in position to permit wheel M to run the aforesaid end of the latch will have been brought below the field of action of the cross-piece b , as in Fig. 2. It will be observed in Fig. 3 that the slot e^1 in one sleeve is somewhat wider than the diameter of the pin e^5 on the other sleeve, whereby one sleeve may be susceptible of a limited rotary play independent of the other. In locking the sleeves together, as in Fig. 2, a like latitude of independent rotary play between the sleeves should be provided for, in which way a too sudden positive application of the brake is avoided and the parts rendered less liable to damage.

What I claim as my invention is—

1. The combination, with the cylinder in a

music-box, of a rotary speed-regulator connected by power-transmitting mechanism with the cylinder, and comprising a friction device, a pair of pivoted governing-arms, and a spring interposed between said arms and friction device, whereby the application of the latter against a stationary stop or abutment is controlled from and by the position of the arms through the medium of the spring and the condition of the said arms determined by the velocity with which they are revolved, substantially as described.

2. The combination, with the cylinder of a music-box, of the arms A and A' , pivotally connected with a rotary support, the acting portion E' of the friction device or brake, and a spring placed in a connection between said friction device and the pivoted arms, substantially as described.

3. In a music-box, the arms A and A' , pivotally connected with a rotary spindle, in combination with the two-part sleeve provided with end collars, E and E' , and the spring interposed between said collars, substantially as described.

4. The combination, with the cylinder in a music-box, of the rotary spindle B , driven from the axle or journal of said cylinder, the collars E and E' , having sleeves e^1 and e^2 and loosely fitted upon said spindle, the spring applied between the two collars, and the bearing F , in which the upper end of the spindle is arranged to turn, substantially as described.

EDWARD SUEUR.
